DESIGN FOR A ROCKING HORSE

Albert E. Jury, Clearfield, Pa.

Application March 15, 1945, Serial No. 118,498

Term of patent 14 years

(Cl. D34—15)

To all whom it may concern:

Be it known that I, Albert E. Jury, a citizen of the United States, residing at Clearfield, in the county of Clearfield and State of Pennsylvania, have invented a new, original, and ornamental Design for a Rocking Horse, of which the following is a specification, reference being had to the accompanying drawings, forming part thereof.

Figure 1 is a side elevational view of a rocking horse showing my new design.

Figure 2 is a top plan view,
Figure 3 is a bottom plan view,
Figure 4 is a front elevational view, and
Figure 5 is a rear elevational view thereof.

I claim:

The ornamental design for a rocking horse, as shown.

ALBERT E. JURY.
